UNITED STATES PATENT OFFICE.

ALBERT W. ENGEL, OF CHICAGO, ILLINOIS.

LOOSE-LEAF ENVELOP-ALBUM.

1,397,000.

Specification of Letters Patent.

Patented Nov. 15, 1921.

Application filed March 13, 1920. Serial No. 365,442.

To all whom it may concern:

Be it known that I, ALBERT W. ENGEL, a citizen of the United States, residing at Chicago, in the county of Cook and the State of Illinois, have invented certain new and useful Improvements in Loose-Leaf Envelop-Albums, of which the following is a specification, reference being had to the accompanying drawings, forming a part thereof.

10 The purpose of this invention is to provide an improved form of loose-leaf album, of which the loose or disengageable and removable leaves are in the form of envelops for containing pictures and the like, and

15 adapted for the insertion of the contents of the envelops and for safe securement of the same therein by closure of the binder. It consists in the elements and features of construction shown and described as indicated in the claim.

20 In the drawings:—

Figure 1 is a perspective view of the loose-leaf binder of which the loose leaves are envelops.

25 Fig. 2 is a plan view of the binder open, and showing one of the loose leaf envelops therein, also open, and contents in said envelop.

30 Fig. 3 is a dissected longitudinal section showing a single envelop between the partly opened covers.

Fig. 4 is a similar transverse section showing the envelop partly open between the partly opened covers.

35 The structure shown in the drawings comprises separable covers of a loose-leaf binder, each consisting of a binding strip, 1, and a cover board, 2, hinged thereto as seen at 3, any means of clamping or tying the cover members together being contemplated, and

40 no specific means being shown, except as indicated by eyelets in the envelops and in the binding strips of the cover member, through which any form of fastening may be inserted. The characteristic of the invention is

45 in the form of the envelop which constitutes a loose leaf, said envelop being formed with the back or main panel, 4, extended beyond the side flaps, the side flaps and one end flap being adapted to be folded upon

the back or main panel in the usual manner, 50 so as to close the envelop at the three edges having such flaps, whereby the open edge of the envelop is the inner end at which the envelop is secured by the extended back panel between the binding strips of the 55 binder. The purpose and the result of this construction, it will be understood, is to cause the only opening through which the contents of the envelop might escape to be at said inner bound end where escape is 60 rendered impossible by the closing of the binder.

Specifically it is desirable that the outer end,—that is, the end opposite the bound end should be permanently closed by sealing the flap at that end onto one of the side flaps, 7, the other side flap 8 being left unsealed to afford opening for inserting contents through that side of the envelop. For the purpose of easy entrance of pictures and 70 like material into the envelop, it is desirable to cut away the edge of the side flap, 7, on an oblique line from the outer open corner toward the inner open end of the envelop as seen at 7a.

75 Any suitable means may be employed for holding the binder closed, as by an elastic band, 10.

I claim:—

A loose-leaf album consisting of the combination with separable cover members, of envelops having one end without a flap and the back or main panel at that end extending for engagement between the cover members of the binder, and having flaps for closing 80 all the other edges; whereby the enveloped contents are secured against escape by the closing of the binder, the envelop being permanently closed at the end opposite that which is engaged between the tongue members and at one side by sealing the flap which closes said end onto one of the side flaps, the other side flap being unsealed for easy entrance of the contents into the envelop when the binder is open.

90 In testimony whereof I have hereunto set my hand at Chicago, Illinois, this 11th day of March, 1920.

ALBERT W. ENGEL.
